CLAIM

The ornamental design for an umbrella misting system, as shown and described.

DESCRIPTION

FIG. 1 is a perspective view of an umbrella misting system; FIG. 2 is a left side elevation view thereof; FIG. 3 is a right side elevation view thereof; FIG. 4 is a front elevation view thereof; FIG. 5 is a rear elevation view thereof; FIG. 6 is a top plan view thereof; FIG. 7 is a bottom plan view thereof; and, FIG. 8 is a perspective view of the umbrella misting system shown in use with environment.

The umbrella misting system is shown broken away in FIGS. 1-7 for ease of disclosure only.

The broken lines depict portions of the article and environment that form no part of the claimed design.
